CONTROLLING PILOT BURNER

Claude M. Garner, Clayton, Mo., assignor, by
mesne assignments, to Missouri Automatic
Control Corporation, a corporation of Missouri

Application October 22, 1946, Serial No. 704,881

9 Claims. (Cl. 158—117.1)

1

The present invention relates to a controlling pilot burner for controlling the flow of fluid to a main burner and in which a control means such as a switch or the like is actuated in response to the presence or absence of flame at the pilot burner.

It is an object of the present invention to provide a simple, rugged and dependable controlling pilot of this kind which is very quickly responsive to the presence or absence of flame.

A further object of the present invention is to provide a device of this character in which two elements of substantially the same co-efficient of thermal expansion are associated with the pilot burner such wise that, when the burner has a flame, one of the elements will be heated to a greater degree than the other one, or will be heated more rapidly and maintained at a somewhat higher temperature than the other one so long as the flame persists, whereby a switch, or the like, may be actuated by the resulting differential in the expansion of the elements, and in which the other element will be heated almost as much as the one, so that a maximum positional differential is obtained.

A further object is to provide a device of this character having a particularly efficient temperature responsive device comprising a pair of elongated expandable elements which are rigidly connected at spaced points and which are weakened coextensively for a relatively short distance between their connected points so that when one of the elements is heated to a higher temperature than the other, substantially all of the warping due to the differential in the elongation between the connected points will occur in the short coextending weakened portions, thereby to achieve greater actuating motion per degree of temperature differential in the two elements.

It is a further object of the present invention to provide, in a mechanism of this kind, a particularly accurate and dependable control.

Other objects and advantages will appear from the following description and the accompanying drawings, in which:

Fig. 1 is a front elevation of a controlling pilot burner constructed in accordance with the present invention;

Fig. 2 is a side elevation of the pilot burner taken from the right of Fig. 1;

Fig. 3 is a rear elevation of the device taken from the right of Fig. 2;

Fig. 4 is an enlarged plan view;

Fig. 5 is an enlarged vertical section through the center taken from front to rear;

2

Fig. 6 is a fragmentary view showing the upper portion of the thermally-responsive elements in an exaggerated operational position;

Fig. 7 is a cross sectional view of the temperature responsive device taken on line 7—7 of Fig. 2.

Fig. 8 is a wiring diagram of a typical installation.

The control includes, as primary elements, a pilot burner, generally indicated at 10, an igniter therefor, generally indicated at 11, a temperature-responsive device, generally indicated at 12, and an actuated device, here shown as a switch, generally indicated at 13.

15 The pilot burner is provided with a deep channel-form base support member 15 that has a connecting portion or web 16 and two plate-like wings or flanges 17 and 18. These flanges may be provided with suitable mounting means such as the notch 20 and hook 20a on the flange 18 by which the pilot burner may be attached to a main burner.

20 The pilot burner 10 is mounted between the two flanges 17 and 18. The pilot burner includes a base portion 22 that preferably is flat-sided, so that it may be supported against the inner surfaces of the flanges 17 and 18 and secured thereto by screws 23. This base portion 22 has a longitudinal passage 24 therethrough and is adapted to receive at its lower end a fitting 24a by means of which a pilot fuel line 25 is connected thereto. The fitting 24a is provided with a fuel metering orifice plate indicated at 25a.

25 The pilot burner 10 further includes an upper cylindrical nozzle portion 26 which interfits with a short reduced cylindrical portion 26a provided at the top of the base 22 and it is connected thereto by rivets 27. This nozzle portion 26 is hollow so as to receive the fuel from the passage 24. At the upper end and at the front of nozzle 26 is a relatively large port or jet 28 at which the main pilot flame is produced. Extending halfway around the nozzle from jet 28

30 is a flame propagation slot 29 which serves to ignite a series of jets 30 arranged down the side of the burner opposite to port 28. On the same side as burner 28 and slightly below is a relatively small igniter jet 31.

35 An igniter is disposed adjacent the igniter jet 31 at a point sufficiently close to the jet to insure ignition, but sufficiently below the jet to avoid direct impinging of the flame on the igniter. The igniter element consists of a coil 32 of platinum wire, or the like, which is suspended between two forwardly projecting arms

33 and 34 which are formed as parts of conductor members 35 and 36. The conductor members lie along opposite sides of the pilot burner 26. The members 35 and 36 are provided with downwardly and rearwardly projecting arms 37 and 38.

The conductor members 35 and 36 are attached to opposite sides of the burner head 26 by 4 screws 39, 39a, 40 and 40a. Suitable insulating strips 41 and 42 are disposed between the members and the burner head. Also 4 insulating washers 43, 43a, 44 and 44a are arranged outside of the conductor members and between them and the screws. The conductor members are thereby effectively insulated from the pilot burner.

The two rearwardly and downwardly projecting arms 37 and 38 receive screws 45 and 46, by means of which terminal clips 47 and 48, respectively, are attached. These terminal clips are adapted to connect a pair of leads 49 and 50 to the conductor members 35 and 36 respectively, and thereby to the opposite ends of the platinum wire igniter coil 32.

The temperature-responsive device 12 is of the rate-of-change type having two elements 51 and 52 constructed of material having substantially the same co-efficient of expansion which lie alongside each other in spaced relationship and which are secured together at the extremities of their effective length. Front or hot element 51 is disposed with relation to burner head 26 so that flames fed by the series of jets 30 will directly impinge upon it. It is provided with forwardly extending flanges 53 which co-extend with the series of burner jets 30 and which shield the flames issuing from these jets at their outer ends from stray drafts, thus insuring uniform rate of heat absorption by element 51. Flanges 53 are tapered, diminishing in width toward the top. This provision promotes generally better flame characteristics.

Element 51 is further provided at its lower end with a forwardly formed lip 59 which serves as a flame baffle to protect the switch structure 13. The rear or cold element 52 is arranged as indicated so as to be shielded from direct flame by the element 51.

At its upper end element 51 is provided with rearwardly extending flanges 54, see Fig. 4, which are overlaid by similar forwardly extending flanges 55 on the rear or cold element 52. Flanges 54 and 55 are securely connected as by spot-welding at 56 thereby securely fastening elements 51 and 52 at their upper ends. Element 52 is also provided with forwardly extending flanges 60 having extensions 57 which overlay flanges 53 on element 51 near its lower end. These flange extensions 57 of element 52 are also securely connected to the flanges 53 of element 51 in a suitable manner as by spot-welding at 58. Elements 51 and 52 are thus spaced laterally as indicated and securely fastened at the extremities of their effective length. The effective lengths of elements 51 and 52 in which elongation is effective to warp the elements is therefore the length between the connected points 56 and 58. Element 52, although its length as a temperature responsive elements ends at the connection 58, has an integral downward extension 52a provided with relatively wide flanges indicated at 52b and which interfits with the deep channel-form support member 15 and is fastened to the web portion 16 thereof by a bolt 68. The temperature

responsive device is thereby supported at its lower end.

There is a motion transmission member 65 arranged parallel with and between elements 51 and 52 which has its upper end securely attached to the upper end of element 52 as by spot-welding and which extends downwardly to a free end which is arranged to actuate the switch 13. The lower end of member 65 carries a threaded adjustable contacting member 66, which is provided with a non-conducting tip 67.

Elements 51 and 52 are stiffened throughout their lengths between their connected points by flanges 53 and 60 and by formed stiffening ribs 61 and 62 respectively, see Fig. 7, with the exception of a short length on each element near their upper ends as indicated at 63 and 64. These short unstiffened portions which extend between the lower ends of flanges 54 and 55 and the upper ends of flanges 53 and 60 may be further weakened by cutting away portions of the web of both members as indicated at 64a in Fig. 3. With this substantial reduction in section modulus at these portions it will be seen that warping due to any expansion differential of the two elements will be substantially limited to these weakened portions and that the point of tangency of the warp curve with the unwarped stiffened portions will be at the upper ends of flanges 53 and 60. See Fig. 6 in which this warping is exaggerated to more clearly illustrate.

There are particular advantages in this arrangement. First; greater deflection or curvature of the elements per degree of temperature differential results with this design and consequently a greater actuating movement per degree of temperature differential is achieved. This is true because the differential in total elongation of any elements between their connected points resulting from a temperature differential is effective to warp only the comparatively short weakened portions, which results in a greater angular deflection per degree of temperature differential than would occur if the elements were of uniform section throughout the distance between their connected points. This will be readily understood when considering that for any given differential in the elongation of two members connected as in this case; the shorter the length of the elements the greater will be their curvature. Also, the total elongation or differential of elongation is proportional to the effective length of the elements when differentially heated, so that when the total differential of elongation obtained by the longer total effective length of the elements is constrained by stiffening to act on only a relatively short section of the effective length of the elements, then a greater curvature in the short sections will occur than if the elements were of uniform section throughout their effective length and the curvature therefore uniform throughout their effective length. Further, in the compact arrangement which is employed in the present invention for the multiplication and transmission of this angular deflection, it is apparent that for a given angular deflection at the upper end of element 65, the shorter the arc the less the upper end of member 65 will move to the right with respect to the actuated switch blade 73 and as a result there will be a greater net movement toward the left at the lower end of member 65. Secondly; a much more rigid and durable instrument may be constructed in following these principles.

Switch 13 is of the single-pole, double-throw

type, having contacts 69, 70 and 71 supported on resilient switch blades 72, 73 and 74 respectively. The switch blades are stacked on bolt 68 with suitable insulating separators in a conventional manner as indicated. The bolt 68 therefore rigidly secures the switch structure and the temperature responsive device to the support member 15. Switch blade 73 is so formed as to normally hold contacts 70 and 71 in a closed position. Stop strips 75 and 76 are provided for switch blades 72 and 74 respectively. Switch blade 74 and stop strip 76 are perforated at 77 to provide access to the switch blade 73 for the actuation thereof by contacting member 66 on the lower end of motion transmission member 65. The lower ends of the switch blades 72, 73 and 74 and the various leads attached thereto are encased in heat-resisting, waterproof, hard-setting cement 78 for the purpose of rigidly fixing the leads and protecting the connections against moisture and corrosive atmosphere. The web portion 16 of support member 15 has a lower integral extension 16a formed at a right angle thereto. The extension 16a is perforated and receives a bushing 16b which receives an armored conduit 103 in which leads to be described hereinafter are contained.

In the wiring diagram, Fig. 8, a typical adaptation of the present invention is illustrated. In this arrangement a normally closed main burner fuel supply control valve is indicated at 79 having an operating coil 80 which, when energized, opens the main valve. A controlling and energizing circuit for the coil 80 is provided and includes a main-transformer secondary winding 81, a lead 82, the valve operating coil 80, a lead 83, a space or room thermostatic switch 84, a lead 85, a heat production limit switch 86, a lead 87, the controlling pilot switch blade 72, the contacts 69 and 70, the switch blade 73 and a lead 88 back to the other side of transformer secondary 81.

A circuit for the energization and control of the controlling pilot igniter 32 is provided and includes an igniter-transformer primary winding 89, a lead 90, the switch blade 74, the switch blade 73, the lead 88, the main-transformer secondary winding 81, a lead 91, a push-button switch 92, a lead 93 back to the other side of the igniter-transformer primary winding 89 and a circuit in parallel with lead 90, including the igniter-transformer secondary winding 94, a lead 95, the lead 50, the igniter coil 32, the lead 49, and the common lead 90 back to the other side of the igniter-transformer secondary winding 94.

A pilot flame indicator light 96 is also provided, having a circuit therefor connected through the primary winding 89 of the igniter-transformer and which includes the lead 93 connected to one side of the primary winding 89, a lead 97, a resistor 98, the light 96 and a lead 99 back to the other side of the primary winding 89. Alternating current is supplied to the primary winding of the main-transformer 100 by commercial lines 101 and 102.

In operation

When the controlling pilot is not burning, the pilot switch 13 and the actuating arm 65 will assume the positions indicated in Fig. 5; that is, the contacts 70 and 71 will be closed due to the rightward urging of formed switch blade 73 and the no-flame position of the lower end of motion-transmission member 65 which permits the closing of these contacts. Fuel is supplied to the

burner head 26 through the fuel line 25 and passage 24 from which it issues at the jets 28, 30 and 31 and slot 29. The control of fuel flow through the fuel line 25 may be by any suitable means such as a hand operated valve not shown.

To light the pilot burner, the fuel valve controlling line 25 is opened and the push button switch 92 is closed. Closing of the push-button switch 92 will cause the energization of igniter coil 32 by completing the following circuit; starting at switch 92, lead 93, igniter-transformer primary winding 89, lead 90, switch blade 74, contacts 70 and 71, switch blade 73, lead 88, main-transformer secondary 81, and lead 91 back to push-button switch 92, which will in turn energize the closed igniter-transformer secondary circuit which includes the lead 95, lead 50, igniter coil 32, lead 49 and the common lead 90 back to the secondary winding 94. With the energization of ignition coil 32, ignition will take place at jet 31 first, thereafter ignition will progress to the main pilot flame jet 28 immediately above, thence around the burner head via the slot 29 and finally down the series of ports 30.

The flames burning at ports 30 impinge directly on the hot element 51 over substantially the full length thereof causing rapid absorption of heat and elongation of this element. Due to their being securely connected at both ends the elongation of element 51 will cause warping of both elements 51 and 52. This warping will be substantially confined to the short portions 63 and 64 near the upper ends of the elements for the reasons hereinbefore explained. This will cause the inclination to the right of the upper flanged ends of the elements and consequently the upper end of motion-transmission member 65, causing its lower end and contacting member 66 to move to the left. Switch blade 73 will be moved thereby toward the left opening contacts 70 and 71 and closing contacts 69 and 70.

The opening of contacts 70 and 71 will break the igniter energizing circuit and also the circuit for signal light 96. The closing of contacts 69 and 70 will establish the following closed circuit for energization of the operating coil 80 of the main burner fuel supply valve; switch blade 73, lead 88, main-transformer secondary 81, lead 82, valve operating coil 80, lead 83, room thermostatic switch 84, lead 85, heat production limit switch 86, and lead 87 back to contact 69. The energization of the valve operating coil 80 will cause the opening of the main burner fuel valve, admitting fuel to the main burner, which is ignited by the main pilot flame issuing from port 28.

In event of flame failure at the pilot burner for any reason, element 51 will lose temperature rapidly, causing both elements to move toward their unwarped no-flame position shown in Fig. 5, and the lower end of member 65 and contacting member 66 will move toward the right, permitting the formed spring blade 73 to open the contacts 69 and 70, breaking the energizing circuit of the operating coil 80, thus cutting off fuel to the main-burner. As element 51 cools further, contacts 70 and 71 will be closed, thus readying the pilot ignition-circuit for operation by the push-button 92.

It may be well to point out that the time required in this device to actuate the switch mechanism in either direction, due to ignition or flame failure, is in the order of 12 seconds.

The foregoing description is intended to be illustrative and not limiting and the exclusive use

of all modifications within the scope of the appended claims is contemplated.

I claim:

1. In a device of the class described, a support member, a device to be actuated mounted on said support member, an elongated temperature responsive device supported at one end by said support member and extending therefrom to a free end, said temperature responsive device comprising a pair of elongated elements lying alongside each other and being rigidly connected at their inner and outer ends and being freely movable with relation to each other between their connected points to expand and contract differentially, both of said elements being stiffened throughout their length with the exception of a short portion on each of said elements lying between their connected points and closely adjacent their outer ends which portions are substantially weakened against transverse bending said weakened portions being coextensive, whereby when one of said elements is heated to expand more than the other, substantially all deflection will occur in both elements in the short weakened portions near their outer ends and whereby less transverse displacement of the outer end of said device for a given deflection thereof will occur, and an actuating arm having one end attached to the outer end of said elements and extending therewith toward said support member for engaging said device to be actuated.

2. In a device of the class described, a rigid support member, an elongated temperature responsive device supported at one end on said support member and extending therefrom to a free end, said temperature responsive device comprising a pair of elongated elements having substantially the same coefficients of expansion arranged substantially parallel and being spaced from each other except at their ends at which they are rigidly connected to each other, both of said elements being stiffened throughout their lengths between their connected points except for a short portion on each element lying between their connected points and closely adjacent their outer free ends which portions are substantially weakened against transverse bending, said weakened portions being coextensive whereby when one of said elements is heated to a higher temperature than the other, substantially all warping will occur in said weakened portions near one end and whereby less transverse displacement of the outer end of said device for a given deflection thereof will occur, and an actuating arm having one end connected to the outer deflecting end of said device and extending toward said support member to a free end.

3. In a heat responsive device, a pair of elongated elements arranged alongside of each other and rigidly connected near their ends and being spaced from each other throughout the distance between said connected points thereby to reduce heat transfer from one of said elements to the other, both of said elements being stiffened throughout their lengths with the exception of one relatively short portion of each of said elements lying between said connected points which portions have a substantially reduced section modulus, said short portions being coextensive and near one end of said elements whereby substantially all warping due to the total differential in expansion of the elements between their connected points will be caused to occur in said short coextending weakened portions near one end of said elements when one of said elements is heated

more than the other between their connected points, means for rigidly supporting said elements at their opposite end, an actuating arm attached to the free warping end of said elements and extending substantially parallel therewith toward their supported end, and means for heating one of said elements to a higher temperature than the other between said connected points.

4. In a heat responsive device, a pair of elongated elements arranged alongside of each other and rigidly connected at first and second spaced points and being spaced from each other throughout the distance between said connected points thereby to reduce heat transfer from one of said elements to the other, both of said elements being stiffened throughout their lengths between said connected points except for one relatively short portion of each of said elements lying between said connected points which portions are substantially weakened against bending, said short portions being coextensive and near said first connected point whereby substantially all warping due to the total differential in expansion of the elements between their connected points will be caused to occur in said short coextending weakened portions near said first connected point when one of said elements is heated more than the other between their connected points, means for rigidly supporting said elements including an additionally stiffened portion of one of said elements extending beyond said second connected point, an actuating arm attached to said elements at said first connected point and extending toward said support, and means for heating one of said elements to a higher temperature than the other between said connected points.

5. In a heat responsive device, a pair of elongated elements having substantially the same coefficient of expansion and arranged alongside of each other, said elements being rigidly connected near their ends and being spaced from each other throughout the distance between said connected points, both of said elements being stiffened throughout their lengths between said connected points except for one short portion of each of said elements lying between said connected points which short portions have a substantially reduced section modulus, said short portions being coextensive and near one end of said elements whereby substantially all warping of the elements due to the total differential in expansion of the elements between their connected points will be caused to occur in said short coextending weakened portions near one end when one of said elements is heated more than the other between their connected points, means for rigidly supporting said elements at their opposite end, and an actuating member attached to the warping end of said elements.

6. In a heat responsive device, a pair of elongated elements arranged alongside of each other and rigidly connected at first and second spaced points and being spaced from each other throughout the distance between said connected points thereby to reduce heat transfer from one of said elements to the other, stiffening means for both of said elements throughout their lengths between said connected points except for one portion of each of said elements lying between said connected points which portions are substantially weakened against bending, said weakened portions being coextensive and adjacent said first connected point whereby substantially all warping will be caused to occur in said weakened portions adjacent said first connected point when

one of said elements is heated more than the other between their connected points, means for rigidly supporting said elements at their second connected point, and a motion multiplying arm attached at one end to said elements at their first connected point and extending substantially parallel with said elements toward said support.

7. In a temperature responsive device, a pair of elongated elements lying substantially parallel with each other and rigidly connected near their ends and being freely movable with relation to each other between said connected points to expand or contract differentially, said elements being of substantially uniform section throughout their lengths between said connected points with the exception of a short portion of each of said elements lying between said connected points which portions are substantially reduced in section, said reduced portions being coextensive and near one connected end whereby substantially all warping will occur in said coextensive reduced portions near one end of said elements when one of said elements is heated more than the other between said connected points, means for supporting said elements at their other end, a switching device carried by said support means adjacent the supported end of said elements, and an actuating arm having one end attached to said elements at their free warping end and engaging said switching device at its other end for the actuation thereof.

8. In a controlling pilot burner an elongated burner head having a longitudinally arranged series of burner ports, a heat responsive device comprising a pair of elongated elements lying parallel with each other and rigidly connected near their ends and being spaced from each other throughout the distance between their connected points, said device being arranged parallel with said burner head with one of said elements facing said burner ports and the other of said elements being shielded therefrom, said elements being stiffened throughout the distance between their connected points with the exception of one short portion of each element lying between said connected points which portions are substantially weakened against bending, said weakened portions being coextensive and near one end of said elements whereby when one of said elements is heated more than the other by flame at the burner substantially all warping will be caused to occur in said coextensive weakened portions near one end, means at the other end of said heat responsive device for rigidly supporting one end of said burner and said device adjacent each other in fixed relationship, switching mechanism carried by said support means, and an actuating arm

having one end attached to the free warping end of said device and extending substantially parallel therewith to said switching mechanism thereby to actuate it.

- 5 9. In a temperature responsive device, a pair of elongated elements lying substantially parallel with each other and rigidly connected near their ends and being spaced from each other throughout the distance between their connected points, 10 said elements being stiffened throughout their lengths between said connected points except for one short portion of each of said elements lying between said connected points which portions have a substantially reduced section modulus, 15 said weakened portions being coextensive and near one end of said elements, whereby when one of said elements is heated more than the other substantially all warping will be caused to occur in said coextensive weakened portions near one 20 end of said elements, means for rigidly supporting said elements at their other end, a switching device carried by said support means and adjacent the supported end of said elements, said switching device including a switch blade fixed at one end 25 and having a free end movable to control a circuit and a switch actuating arm having one end connected to the warping end of said elements and having a free end engaging said switch blade at a point intermediate of its ends for the actuation 30 thereof.
